(57) CLAIM

The ornamental design for a novelty smoking article, as shown and described.

DESCRIPTION

FIG. 1 is a front perspective view of a novelty smoking accessory showing our new design;

FIG. 2 is a front plan view thereof;

FIG. 3 is a side view thereof;

FIG. 4 is a bottom view thereof; and,

FIG. 5 is a top view thereof.

The broken lines in the drawings depict parts of the novelty smoking accessory that form no part of the claimed design.
